ELECTRON MULTIPLIER

Erno Winter, Budapest, Hungary, assignor to Egyesult Izzolampa es Villamossagi Reszvenytarsasag, Budapest, Hungary, a Hungarian enterprise

Application February 28, 1956, Serial No. 568,326

Claims priority, application Hungary March 8, 1955

4 Claims. (Cl. 315—12)

This invention relates to improvements in electron multipliers and particularly to electron multipliers adapted to be operated as voltage amplifiers.

In conventional multistage electron multipliers the original input electron current usually originated from a photoelectric current source and the amplification problem has been overcome by application of principles of secondary-emission. For this purpose inside a sealed envelope there are provided a photoelectric cathode, a series of electrodes, so-called target electrodes, all surface-treated with secondary emitting materials and operated at successively higher positive potentials and a collector electrode collecting the electron leaving the last target electrode. As the secondary emission coefficient is usually greater than unity, amplification of the original beam current is achieved by multiplication of the electrons, the gain of the multiplier being δ^n , where δ is the number of electrons emitted from the first target electrode for each electron leaving the cathode and n the number of the target electrodes on which secondary emission is employed. With as many as 15-20 stages gains of several million are possible in a single tube. Work has been done on magnetic and later on electric-field focusing arrangements and the result of the latter development are target electrodes, called dynodes, which has been so shaped and arranged obliquely to one another as to give a focusing effect for electrons proceeding from one target electrode to the next.

Although secondary-emission multipliers have also been applied to amplification of thermionic currents, these devices were not adapted to voltage-amplification. In fact in electron discharge tubes the amplitude of the D.-C. component of the anode-current surpasses by orders of magnitude the amplitude of the A.-C. component of the anode current. By amplifying very low voltages for instance of the order of magnitude of one microvolt, the D.-C. component, the so-called carrier component of the anode-current, would cause an anode-current on the collector of 100-300 amperes. An anode-current of this magnitude would not only be unbearable, but would cause an unavoidable noise in the output circuit completely smothering the amplified signal.

The principal object of the present invention, therefore, is to provide an improved electron-multiplier, especially suited for voltage-amplification.

Another object of the invention is to provide an electron-multiplier adapted to be operated with a current of the order of magnitude of one microampere striking the first target electrode of the electron multiplier with a simultaneous amplifying voltage of the same order of magnitude, thus causing an anode current on the collector of about the same order of magnitude as the anode-current of the terminal tube of a multistage amplifier, whereby the amplitude of the D.-C. carrier component of said anode-current and the amplitude of the A.-C. component of said anode-current are of the same order of magnitude. Thus a single electron-multiplier according to the inven-

2

tion is suited for amplifying voltages of the order of magnitude of one microvolt or even lower voltages, like a multistage amplifier.

Still another object is to provide an electron multiplier adapted to voltage amplification, whereby the signal-to-noise ratio is more advantageous than with usual multistage amplifiers.

In accordance with the invention the improved electron-multiplier comprises a sealed envelope, a thermionic or field emission cathode, a collector, secondary emitting target electrodes located between said cathode and said collector, a set of electrodes for focusing the electron-beam emitted by said cathode and located between said cathode and at least one further electrode located between the last focusing electrode and the first secondary emitting target electrode, the geometrical dimensions of the cross-section of said electron-beam, its electron density, i. e. the number of electrons contained in the unit volume of the electron current flow and the distance between the last focusing electrode and said further electrodes being chosen so as to set up a virtual cathode upon at least one of said further electrodes. Hereby the electron current flow striking the first secondary emitting target electrode is of the order of magnitude of about one microampere.

The electron current flow leaving the cathode is by means of said focusing electrodes concentrated on a slit in one of said further electrodes located between the last focusing electrode and the first secondary emitting target electrode. This further electrode may be a grid, for instance the control-grid of the electron multiplier and is preferably provided with one single slit. The virtual cathode is thus set up on said grid or at least in its close proximity, acting practically as a potential minimum set up by the space charge upon said further electrode so that this electrode may be regarded as the virtual source of the electrons flowing to the first target electrode. As a result of this virtual cathode the slope of the characteristic in the plane of the electrode acting as a virtual cathode will ensure an advantageous actual performance even for 1 ma. plate current. With this small electron D.-C. current the noise-level of the tube is low and the multiplier is adapted to amplify such small currents up to 0.1 ampere, that is up to the magnitude of the plate current of the terminal tube of a high performance multistage amplifier.

One embodiment of my invention is shown in the accompanying drawing in which—

Fig. 1 is a sectional view of an electron amplifier embodying my present invention.

Figs. 2-4 are three different modifications of a grid electrode, adapted to be applied in an electron amplifier according to my present invention, shown on an enlarged scale.

Fig. 5 shows the relationship between plate current and control voltage, the current being plotted in microamperes, the voltage of the control-grid in microvolts. U_4 and U_6 are parameters.

The device comprises an evacuated sealed envelope 260 of glass or any other suitable material in which there is provided a thermionic or field emission cathode 3, secondary emitting staggered target electrodes 9, 10, 11, 12, 13, 14 and 15 and a collector electrode 16. The target electrodes 9-15 are preferably so shaped as to provide curved electric fields thus increasing the effect for electrons proceeding from one target to the next.

Suitable accelerating potentials are impressed upon the target electrodes 9-15 and the cathode 3 by appropriate connections to taps on a voltage divider which, as illustrated, comprises the series connection of resistors 33 to 37 inclusive. A source of relatively high potential, such as a battery 38 is connected to the terminals of the

voltage divider. The negative terminal of the battery 38 is connected to the cathode 3. Between the cathode 3 and a control grid 8 there are provided four focusing electrodes 4, 5, 6 and 7. The control grid 8 has but one tiny slit 17 and the electron beam leaving the cathode 3 is concentrated by means of said focusing electrodes 4-7 just on the slit 17. The narrow beam passing through the slit 17 strikes the first secondary emitting target electrode 9 and the secondary electrons released on the surface of this electrode are attracted by the next following target electrode 10 and, so on thus producing an amplification due to bombardment of the secondary emitting surface in cascade, which are operated at successively higher positive potentials. The secondary electrons released on the surface of the last target electrode 15 of the series are collected by the collector electrode 16.

The first focusing electrode 4 is connected to a tap 40 movable along a standard resistor 41 in series connection to a voltage-source 42, in order to adjust the potential of said first focusing electrode 4. Suitable potentials are impressed upon the focusing electrodes 5, 6 and 7 by appropriate connections to a voltage divider 43, to the terminals of which there is connected a battery 44. In order to control the voltage of the focusing electrode 6 the respective tap 45 is movable along the resistor 43.

The potential minimum set up by the space charge and referred to as a virtual cathode, because it may be regarded as the virtual source of the electron flowing to the plate, i. e. in the tube according to the invention to the first secondary emitting target electrode, forms at a critical value I_{kr} of the electron current leaving the cathode.

$$I_{kr} = \frac{K \cdot F}{D^2} \left(V_{g_{eff}}^2 \frac{1}{2} + V_{a_{eff}} \frac{1}{2} \right)^2$$

where the value of K is a constant

$$K = \frac{\sqrt{2}}{9\pi} \sqrt{\frac{e}{m}} = 2.33 \times 10^{-3}$$

if the voltage is substituted in volts I_{kr} results in milliamperes. F is the cross-section of the electron beam and D the distance between the accelerator-grid and the plate, i. e. in the tube according to the invention the distance between the last focusing electrode 7 and the control grid 8 located between said last focusing electrode and the first target electrode. $V_{g_{eff}}$ is the effective voltage of the last focusing electrode 7 and $V_{a_{eff}}$ the effective voltage of the grid 8 on the hole of which the virtual cathode is set up. (The effective voltage of an electrode is the value of the voltages of all other electrodes located behind said one, reduced to the position of that one electrode.)

Let $V_{g_{eff}}^2 = 50$ volts, $V_{a_{eff}} = 100$ volts, $D = 1$ cm. and $F = 1$ cm.², then:

$$I_{kr} = 2.33 \times 10^{-3} \times (7+10)^3 = 2.33 \times 10^{-3} \times 4.9 \times 10^3 = 11.3 \text{ ma.}$$

If, according to the invention, an electron-beam is produced with a quadrilateral cross-section measuring 0.1×0.01 cm., or 0.002×0.5 cm., the value of F drops from 1 cm.² to 0.001 cm.² and D left unchanged the critical electron current I_{kr} drops from 11.3 ma. to 11.3 microamperes. With these conditions assumed the voltage amplification aimed at will then be realized. Various other values may also be varied. Thus, for instance, with an accelerating voltage, i. e. potential of the last focusing electrode 7 of only 4-5 volts effective and a control voltage on the grid 8 of only 9-16 volts effective and the cross-section of the electron beam measuring 0.001 cm.², the virtual cathode will be set up with an electron current of 1 microampere. Owing to the fact of D being an quadratic factor its variation highly effects the value of I_{kr} .

Since the distance between the virtual cathode and control grid 8 is extremely small, practically equal to

zero and the input attenuation is of a small value, the multiplier tube according to the invention is well adapted to amplify signals in the ultra high frequency range.

The focusing electrode 4 is preferably operated at a negative potential, the focusing electrodes 5, 6 and 7 at positive potentials. The positive potential of the focusing electrode 7 is preferably higher than the positive potential of the focusing electrode 5; the positive potential of the focusing electrode 6 may be varied by means of the potentiometer 43 and tap 45, but is preferably always lower as the potential corresponding to the position of the electrode 6.

To simplify the drawings, only four multiplying stages are shown in Fig. 1. It is to be understood, however, that as many stages as desired may be incorporated into the device.

The efficiency of concentration or focusing of the electron beam leaving the cathode 3 may be increased by means of deflection-plates or pairs of such plates setting up electrostatic deflecting fields, these plates being applied in addition to the focusing electrodes 4, 5, 6 and 7 and arranged between the electrodes 7 and 8.

In Figs. 2-4 there are shown three modified forms of the control grid 8 of the multiplier tube according to the invention.

The control grid shown in Fig. 2 consists of two plane metal sheets 18 and 19 connected to each other by means of strips 20 and 21 in such a way that there remains a tiny slit 22 surrounded by said members 18-21. The hole 22 has been drawn on an enlarged scale. Its dimensions, i. e. its cross-section is preferably of the order of magnitude of the cross-section of the electron beam concentrated by the focusing electrodes 4-7 on said slit 22.

The control grid according to Fig. 3 consists of two plane sheets 23 and 24, connected to each other by means of strips 25 and 26 in such a way that there remains a narrow gap 27 of an oblong form. This gap is also drawn on an enlarged scale. Its dimensions are preferably equal to the dimensions of the electron beam concentrated by the focusing electrodes 4-7 on said gap 27.

This gap may for instance have a height of 1 mm. and a width of 0.1 mm., or a height of 10 mm. and a width of 0.01 mm.

The modified embodiment of the grid shown in Fig. 4 differs from that shown in Fig. 3 in the gap between the plates 28 and 29 and the linking strips 30 and 31, said gap having somewhat greater width. In this gap there is provided a set of very thin wires 32 preferably made of tungsten and each having a diameter of about a few microns. The wires 32 may be arranged longitudinally in the gap as shown in Fig. 4, or crosswise or longitudinally and crosswise; they are provided in the plane of the electrode and span the gap.

The grid 8 to be applied in the tube according to Fig. 1 may also be made of one single piece of sheet metal and be provided with a slit or gap in any known manner.

The material, the various electrodes of the tube are made of, may be any of the commonly used metals or alloys, for instance molybdenum or tungsten. The wires 32 of the grid shown in Fig. 4 may preferably be coated with a thin layer of gold.

The secondary emitting target electrodes 9-15 may be made of an alloy of silver and magnesium or silver and beryllium or brass and may be coated with alkaline metals. Such electrodes are described in the French Patent No. 868,086 and the Hungarian Patent No. 133,334. Other materials may also be used.

Fig. 5 shows the relationship between the plate current and the voltage of the control grid. The lower curve shows the slope for a voltage of -2 volts of the first focusing electrode 4, the higher curve for a voltage of -1 volt of the same focusing electrode. According to theories prevailing up to now the virtual cathode, i. e.

the potential minimum of the space charge is set up with a certain discontinuity. The diagram in Fig. 5 shows no such phenomenon. Discontinuity would result with a perfectly dense cathode, without any hole or gap in it. I have found that the virtual cathode is first set up on the two edges of the gap of the electrode 8, for instance on the longitudinal edges of the gap of the grids shown in Figs. 3 and 4 and then continually expands towards the middle of said gap. The setting up of the virtual cathode is accelerated by means of the thin wires 32 provided in said gap.

The gap 17 in the grid 8 may, however, be of any suitable form, such as a quad, a circular hole, or the like.

Although only one embodiment of the electron multiplier according to the invention has been described, it will be understood by those skilled in the art that this specific form may be modified and the electron-multiplying may be performed according to other known principles without departing from the spirit of my invention and I desire to avail myself of such modifications as come within the scope of the appended claims.

I claim as my invention:

1. A grid-controlled electron multiplier tube for voltage amplification, comprising a thermionic or field emission cathode, a set of secondary emitting target electrodes, a collector electrode, a control electrode having an aperture and disposed between said cathode and said target electrodes, means coating with said cathode for establishing a space charge having predetermined properties in the region of said aperture, said means comprising a set of focusing electrodes disposed between said cathode and said control electrode for concentrating the electrons emitted by said cathode on said aperture in said control electrode, and the physical and electrical parameters of said means and their interrelation being determined by the formula:

$$I_{Kr} = \frac{KF}{D^2} (\sqrt{V_{g_{eff}}} + \sqrt{V_{a_{eff}}})^3$$

where I_{Kr} is the electron beam current to said control

electrode expressed in milliamperes and is of the order of magnitude of one microampere; K is a constant, the numerical value of which is 2.33×10^{-3} ; F is the cross-sectional area in cm.^2 of the electron beam leaving the focusing electrode closest to said control electrode, D denotes the distance between the last-mentioned focusing electrode and said first target electrode in cm. , $V_{g_{eff}}$ is the effective voltage of the last focusing electrode and $V_{a_{eff}}$ is the effective voltage of the control electrode, 10 both in volts.

2. An electron multiplier according to claim 1, in which four focusing electrodes are present.

3. An electron multiplier circuit comprising an electron multiplier according to claim 2, and means for applying suitable voltages to the electrodes of said electron multiplier, in which a negative voltage is applied to the first focusing electrode, positive voltages to each of the other focusing electrodes, to the target electrodes and to the collector electrode, and a control voltage is applied 20 to the control grid.

4. An electron multiplier circuit according to claim 3, in which the positive voltage applied to the fourth focusing electrode is higher than that applied to the second focusing electrode, the positive voltage applied to 25 the third focusing electrode being adjustable and lower than the voltage of said fourth focusing electrode.
